UNITED STATES PATENT OFFICE

99,953

DESIGN FOR AN AUTOMOBILE HEATER

Joseph S. Losee, Hebron, Ill.

Application April 20, 1936, Serial No. 62,225

Term of patent 7 years

To all whom it may concern:

Be it known that I, Joseph S. Losee, a citizen of the United States, residing at Hebron, in the county of McHenry and State of Illinois, have invented a new, original, and ornamental Design for an Automobile Heater, of which the following is a specification, reference being had to the accompanying drawing, forming a part thereof, in which, the figure of the drawing is a perspective view, showing my new design.

The opposite end portion is identical with the end shown in the figure; the back portion of the heater is plain.

I claim:

The ornamental design for an automobile heater, as shown and described.

JOSEPH S. LOSEE.
